CLAIM

The ornamental design for a hat, substantially as shown and described.

DESCRIPTION

FIG. 1 is a top view of a design for a hat;

FIG. 2 is a side view of the design for a hat;

FIG. 3 is a front perspective view of the design for a hat;

FIG. 4 is a front view of the design for a hat; and,

FIG. 5 is a rear view of the design for a hat.

The short hatch marks on the periphery of the triangle-like shapes represent embroidery, and the stippling inside the triangle-like shapes represents material. The entire surface of the hat which is in broken lines is shown for environmental purposes only and forms no part of the claimed design.
